UNITED STATES PATENT OFFICE.

JOHN FREDERICK HENRY HOWARTH, OF MARRICKVILLE, NEAR SYDNEY, NEW SOUTH WALES, AUSTRALIA.

CARBURETER FOR INTERNAL-COMBUSTION ENGINES.

1,255,610.

Specification of Letters Patent.

Patented Feb. 5, 1918.

Application filed June 8, 1916. Serial No. 102,388.

To all whom it may concern:

Be it known that I, JOHN FREDERICK HENRY HOWARTH, a subject of the King of Great Britain and Ireland, residing at 5 "Elystan," 39 Fraser street, Marrickville, near Sydney, New South Wales, Australia, have invented certain new and useful Improvements in Carbureters for Internal-Combustion Engines, of which the following

10 is a specification.

This invention relates to carbureters of the type in which fuel is introduced through a fixed jet within a Venturi choke tube; it consists in certain manually controllable

15 means for varying the "depression" or degree of suction operating at the jet orifice and thereby adjusting the relative proportions of air and fuel in the explosive mixture supplied to the engine.

20 In the accompanying drawings the invention is illustrated by way of example as applied to a carbureter with a vertical tubular barrel in which a Venturi choke tube is fitted.

25 I would have it understood that I do not suggest that there is novelty broadly in the introduction of "additional" air by automatic or manually controlled means above the choke tube in a carbureter of the type described.

30 My invention is restricted to particular means for introducing air into the upper part of the carbureter, "additional" to the air which passes through the Venturi choke tube.

35 According to this invention vertical grooves are cut in the outer part of the choke tube so as to extend back into the uppermost part of the bore of said tube, and said grooves are put in communication with atmosphere thereby to admit air into the mixing chamber at the top of the choke tube, and blow the throttle by rotating the choke tube or a part thereof in the casing. When the control is adjusted to close said grooves,

40 air reaches the mixing chamber only through the throat of the choke tube, but when the control is adjusted so as to bring the grooves into register with the air ports of the casing, more or less air according to the degree of 45 adjustment is permitted to pass into the mixing chamber at the head of the choke tube and to mingle directly with the fuel mixture which is delivered through the choke tube.

50 Figure 1 is a sectional elevation of the

main part of a carbureter having a vertical tubular barrel embodying my invention;

Figs. 2 and 3 are horizontal sections respectively on the lines 2—2 and 3—3 in Fig. 1;

Figs. 4 and 6 are fragment vertical sections corresponding with portion of Fig. 1 respectively illustrating two detail variations in the construction of the grooved choke tube;

Fig. 5 a horizontal section on line 5—5 in Fig. 4;

Fig. 7 a horizontal section on line 7—7 in Fig. 6.

As shown in Figs. 1 to 5 the Venturi choke tube is divided into an upper portion A and a lower portion B on a horizontal line C located about the contraction of the throat. The upper part A is fixed in the barrel D by screw pins E or otherwise, and the lower part B is rotatable in the casing below the part A, its lower edge being supported on an annular flange F. G are grooves (three shown) cut vertically in the outer surface of the choke tube, and H are lands intervening between these grooves and made a neat fit for the barrel D. As will be seen in both these figures, the grooves G break into the upper part of the bore of the choke tube, as shown at J. In the construction shown in Fig. 1 they extend through the bottom of the choke tube ring B and communicate at O with the foot box P of the carbureter. In the construction shown in Fig. 4 they stop short of the bottom edge of the choke tube ring B which rests on the annular flange F at the bottom of the casing D. K (Figs. 4 and 5) are air ports in the casing D around the location of the choke ring B; these holes form a means of communication between the grooves G in the choke ring B and outer atmosphere. The ring B is rotatable in the casing D between the fixed part A of the choke tube and the seating flange F by means of an arm L movable through a slot in the casing D; said arm L is connected by rod, flexible wire, or other usual control device to a hand lever (not shown) which is fitted conveniently within the driver's reach.

The lands H are a little wider than the grooves G so that when the choke ring B is turned to bring its lands into alignment with the grooves in the fixed part A of the choke tube communication from outside air to the

upper part of the carbureter through the grooves is shut off. When however, the ring B is turned so as to bring its grooves to a greater or less extent into alinement with the grooves in the fixed part A of the choke tube, a proportionate amount of air may pass through said grooves from the atmosphere and mix at the top of the choke tube with the fuel mixture therein, which is constituted of fuel delivered through the jet Q and air, which has passed through the throat of the choke tube A-B and absorbed said fuel.

Air may be admitted to the mixing chamber R in a similar way by rotating the whole choke tube—which in this case is not divided—and disposing the air ports K so that, as it is rotated, a greater or less area of said holes is exposed to admit atmosphere into the grooves, as shown in Figs. 6 and 7; but it is preferable to fix the upper part of the choke tube and to fit its lower portion as an independent control ring as shown in either Fig. 1 or Fig. 4, the upper part A of the choke tube then forming a seating against the top surface of the ring B.

What I claim as my invention and desire to secure by Letters Patent is:—

1. In a carbureter, the combination of a tubular barrel, a horizontally divided Venturi choke tube inclosed in said barrel and having its upper section fixed therein and its lower section rotatable therein, both sections of the said choke tube having grooves cut lengthwise in their outer surfaces, the

grooves extending into the uppermost part of the throat of said tube and being in communication with the atmosphere at their lower ends, and having lands between them of greater width than said grooves, a means for partially rotating the lower section of the said choke tube, thereby more or less displacing the grooves in the two sections of the choke tube, relative to each other and a fuel jet located in said choke tube. 40 45

2. In a carbureter, the combination of a tubular barrel and a horizontally divided Venturi choke tube inclosed in said barrel and having its upper section fixed therein and its lower section rotatable therein, both sections of the said choke tube having grooves cut lengthwise in the outer surfaces, the grooves extending into the uppermost part of the throat of said tube and through the lower section thereof into the foot box 50 55 of the carbureter, and having lands between them of greater width than said grooves, a means for partially rotating the lower section of the choke tube thereby more or less displacing the grooves in the two sections of the choke tube relative to each other to admit a variable supply of air from said foot box into the mixing chamber, and a fuel jet located in said choke tube. 60

In testimony whereof I have affixed my 65 signature in presence of two witnesses.

JOHN FREDERICK HENRY HOWARTH.
